LANTERN

Max Kushner, Brooklyn, N. Y.

Application December 15, 1949, Serial No. 6,636

Term of patent 14 years

(Cl. D48—4)

To all whom it may concern:

Be it known that I, Max Kushner, a citizen of the United States, residing at Brooklyn, New York, in the county of Kings and State of New York, have invented a new, original, and ornamental Design for a Lantern, of which the following is a specification, reference being had to the accompanying drawing, forming part hereof.

In the drawing:

Fig. 1 is a front elevational view of a lantern, showing my new design;

Fig. 2 is a side elevational view;

Fig. 3 is a rear elevational view; and

Fig. 4 is a bottom plan view of the same.

Both side views of the lantern are similar.

I claim:

The ornamental design for a lantern, as shown and described.

MAX KUSHNER.
